DRAFT RIGGING FOR CONCRETE RAILWAY CARS

Original Filed Oct. 31, 1918

INVENTOR.

BY
F. M. Wright.

ATTORNEY.

UNITED STATES PATENT OFFICE.

ARTHUR C. GRIEWANK, OF OAKLAND, CALIFORNIA.

DRAFT RIGGING FOR CONCRETE RAILWAY CARS.

Original application filed October 31, 1918, Serial No. 260,434. Divided and this application filed
August 9, 1919. Serial No. 316,483.

The object of the present invention is to provide an improved draft gear for railway cars.

The present application is a division of an application filed by me on Oct. 31, 1918, Serial No. 260,434.

In the accompanying drawing, Figure 1 is a horizontal section through an end of a car, showing in detail my improved draft rigging; Figure 2 is a view similar to Figure 1 on the line 2—2 of Figure 1.

Referring to the drawing, 41 indicates the floor of a concrete railway car. In a recess 43 extending at the end of the car, are contained three longitudinally extending horizontal helical springs 44, (Fig. 1.). In the center of each spring extends an eye-bolt 46, the eye of said bolt surrounding a vertically extending bolt 47 surrounded by upper and lower pipes 48 embedded or secured in the outward extension 49 of the adjacent bolster 6 or directly to bolster 6, the lower ends of said bolts having cotter pins 51, therethrough, the heads of said bolts preventing them from falling down. The inner ends of said springs press against a vertical member or follower 52 of an angular plate 53 (Fig. 2), which member either in turn presses against a sheet 54 of shock-absorbing material, which in turn is pressed against the outer surface at the inner end of said recess. The outer ends of said springs 44 press against the inner surface of an outer member or follower 56, which is held by nuts 57 on the outer ends of said eye-bolts 46, which latter extend through holes 58 in said rocker. The central portion of the outer side of said rocker is curved convexly and bears against a vertically extending portion of the U-shaped bridle plate 59 forming a part of the coupler 66. This plate is connected by bolts 61 and nuts 62 to said angular plate 53, the heads of said bolts 61 being curved convexly on the surfaces adjacent to said plate 53 to rock thereon, the sheet 54 having holes 63 to receive said heads. The bridle plate 59 is fixedly connected by vertical bolts 64 to the inner end of the coupler 66. The coupler 66 extends through a comparatively narrow opening 67 in the front end of the body of the car. A transversely extending retaining plate 68 is secured to the horizontal member of the angular plate 53. Side chafing plates 71 receive the impact of the ends

of the rocker. A chafing and supporting channel-iron 69 is secured to the plates 71 and closes the opening beneath the springs between the horizontal member of the angular plate 53 and the rocker 56.

I claim:—

1. In combination with a railway car body, a longitudinally extending device the inner ends of which are secured to said body, an outer member slidable upon said device and limited in its outward movement thereby, coiled springs pressing said outer member outwardly, an inner member pressed inwardly by said springs, shock absorbing material between said inner member and the car body, a coupler, and devices for connecting the coupler with the inner member.

2. In combination with a railway car body, bolts, fixedly secured to said car body, inner and outer members through which said bolts extend, said outer member being formed with a convex outer surface, a coupler bearing against said convex surface, springs between said inner and outer members, said bolts limiting the outward movement of the outer member, a tension device connecting said coupler with said inner member, and said springs and tension device limiting the movement of the coupler.

3. In combination with a car body, a spring, a bolt secured at one end to said car body, an inner plate through which the bolt extends and against which said spring presses, a rocker through which the bolt extends and against the inner surface of which said spring presses, means for limiting outward movement of said rocker, a bridle plate on which said rocker bears, means for connecting said bridle and inner plates, a coupler, and means for connecting said coupler with the bridle plate.

4. In combination with a car body, springs, bolts extending through the springs, means for securing the inner ends of the bolts to said body, an inner plate against which said springs press, a rocker against the inner surface of which said springs press, the outer side of said rocker being curved, means on the outer ends of said bolts which retain said rocker against forward movement, a coupler, a bridle plate attached to said coupler, and engaging the curved surfaces of said rocker and bolts connecting the inner plate to said bridle plate.

5. In combination with a car body, springs, an inner plate against which the inner ends of said springs press, a rocker against the inner surface of which the outer ends of said spring press, bolts anchored to said body and means for supporting the outer ends of said bolts upon said rocker, a bridle plate, said rocker having its outer side curved which allows a radial movement of a 10 coupler, bolts connecting said bridle plate and inner plate with one another, a coupler and means for connecting said coupler with the bridle plate.
6. In combination with a railway car body, 15 longitudinally extending members the inner ends of which are secured to said car body, an outer member slidable on said members, springs pressing said outer member outwardly, an inner member supported by 20 said longitudinally extending members and pressed inwardly by said springs, a coupler, devices for connecting the coupler with the inner member permitting inward movement of the coupler relative thereto, a member 25 supported transversely by said car body and extending under and slidably supporting said outer member and an extension carried by said inner member and having sliding engagement with said transversely extending member.
7. In combination with a car body, longitudinally extending devices, the inner ends of which are pivotally secured to said body and an outer member slidable upon said devices and limited in its outward movement thereby, springs pressing said outer member outwardly, and an inner member pressed inwardly by said springs, a coupler and devices for connecting the coupler with the inner member.
8. In combination with a car body, bolts, means by which the inner ends of said bolts are pivotally secured to said car body, inner and outer members, through which said bolts 45 extend, springs around said bolts between the said outer and inner members, devices on the said bolts for limiting the outward movement of the outer member, a coupler, a tension device extending between said coupler and said inner member and provided with devices for limiting the outer movement of the coupler upon the inner member and
- curved surfaces on said tension member and outer member, for a radial movement of said coupler.
9. In combination with a car body, a longitudinally extending device, the inner ends of which are pivotally secured to said body, an outer member slidable upon said device and limited in its outward movement thereby, springs pressing said outer member outwardly, an angular inner member pressed inwardly by said springs, a coupler, said outer member having curved surfaces for the radial movement of said coupler, and devices 60 for connecting the coupler with the inner member.
10. In combination with a car body, springs, bolts extending through the springs, means for pivotally securing the inner ends 70 of the bolts to said body, an angular inner member against which said springs press, which in turn presses against the car body, a rocker against the inner surface of which said springs press, means on the ends of said 75 bolts for limiting the outward movement of said rocker, said rocker having an outer curved surface, a bridle plate engaging said curved surface to allow a radial movement of said bridle plate, bolts passing on the outside of said springs connecting said bridle plate and inner member, means by which the last named bolts can have lateral movement in respect to said inner member, a coupler, a means for fixedly connecting said 80 coupler with the bridle plate.
11. In combination with a car body, springs, bolts extending through the springs, means for securing the inner ends of the bolts to said body, an inner plate against 85 which said springs press, which in turn presses against the car body, a rocker against the inner surface of which said springs press, means for supporting the outer ends of said bolts upon said rocker, said rocker having an outer curved surface, a bridle plate engaging said curved surface, bolts passing on the outside of said springs connecting said 90 bridle and inner plates, means by which the bolts can have lateral movement in respect to said inner plate, a coupler and means for connecting said coupler with the bridle plate.

ARTHUR C. GRIEWANK.
